DES. 2035

David Heathstone of Albany N.Y.
Letter Patent No 2135 Dated Feb 25, 1825

Ornamental design for the plates of a Corks Store.

The Schedule referred to in the Letter Patent and making part of the same,

Be it known, that I David Heathstone of the City of Albany, and State of New York, have produced a new ornamental design for the plates of a Corks Store, and I declare the annual drawings (photograph) of the Water-Stove, so called, exhibiting in perspective a stove with the plates in place, to be a full and correct delineation of the said plates with their ornaments. The oven and furnace doors not represented, being symmetrical, similar to those shown in the drawings.

What I claim as my production and desire to secure by Letters Patent is the combination and arrangement of figures and forms above referred to, represented in the accompanying drawings, joining together an Ornamental design for the plates of a Corks store.

David Heathstone
